UNITED STATES PATENT OFFICE.

WILLIS JONES, OF BUFFALO, NEW YORK.

DESIGN FOR A KNIFE-HANDLE.

SPECIFICATION forming part of Design No. 33,681, dated December 11, 1900.

Application filed October 20, 1900. Serial No. 33,783. Term of patent 3½ years.

To all whom it may concern:

Be it known that I, WILLIS JONES, a citizen of the United States, residing at Buffalo, in the county of Erie and State of New York, have invented and produced a new and original Design for Knife-Handles, of which the following is a specification, reference being had to the accompanying drawings, forming part thereof.

10 This invention consists in a design for a knife-handle, as illustrated in the accompanying drawings, of which—

Figure 1 is a side elevation of my design. Fig. 2 is a cross-section taken through the line 15 X X. Fig. 3 is a cross-section taken through the line y y. Fig. 4 is a cross-section taken through the line g g.

Referring to the drawings, 1 1 are the side walls or body of the knife-handle. Extending along the back face of the knife-handle and covering the back edges of the side walls 20 is the strip 2. The side walls of the knife-handle, which present flat surfaces, are cut

curved at one end, as at 3 and 4, and have the semicircular edge 5, extending from the curve 25 3 to the end 6 of the knife-handle, and in this portion of the walls 1 are cut the orifices 7, having inclined walls tapering inwardly.

The leading feature of the design consists in the strip 2, extending over the full breadth 30 of the back of the handle for about three-fourths of its length. Minor features are the curved portions 3 and 4, semicircular edge 5, and orifices 7.

Having thus described my invention, what 35 I claim, and desire to secure by Letters Patent, is—

The design for a knife-handle substantially as shown and described.

In testimony whereof I have signed my 40 name to this specification in the presence of two subscribing witnesses.

WILLIS JONES.
